BODY JACK ATTACHMENT

George M. Walraven, Kenosha, Wis., assignor to
Snap-On Tools Corporation, Kenosha, Wis.

Application August 4, 1939, Serial No. 288,307

5 Claims. (Cl. 254—100)

This invention relates to mechanical jacks and more particularly to attachments for automobile body jacks, although certain features thereof may be employed with equal advantage for other purposes.

It contemplates more especially the provision of an adjustable work engaging attachment for a body jack to render the jack more effectively applicable for sustaining, reinforcing and straightening angular irregularities of an auto body resulting through accident or impact.

One object of the present invention is to simplify the construction and improve the operation of devices of the character mentioned.

Another object is to provide an improved body jack attachment of simple and compact construction that will operate with minimum wear and effort in the use thereof.

Still another object is to provide a rotatable end attachment for a body jack that is of durable and rugged construction to operate with minimum wear and effort.

A further object is to provide a simple and improved rotatably mounted end attachment for a body jack capable of being securely locked at any desired angle for operation without any appreciable wear on the acting elements.

A still further object is to provide improved means for maintaining a rotatable attachment for a body jack at any desired angle in the plane of said body jack.

Still a further object is to provide a simple, rugged locking means for a rotatable end attachment for a body jack.

Other objects and advantages will appear from the following description of an illustrative embodiment of the present invention.

In the drawings:

Figure 1 is a front view in elevation of a body jack showing the assembled spoon attachment embodying features of the present invention.

Figure 2 is a sectional view of the spoon attachment taken substantially along lines II—II of Figure 1.

Figure 3 is a fragmentary sectional view of the body jack spoon attachment taken substantially along line III—III of Figure 2.

Figure 4 is a front view in elevation of a modified embodiment of the body jack attachment.

Figure 5 is a top plan view of Figure 4.

Figure 6 is a sectional view taken substantially along line VI—VI of Figure 5.

Figure 7 is a side view in elevation of the axial pin shown in Figure 6 with parts thereof being broken away to clarify the showing.

The structure selected for illustration comprises an elongated tubular cylindrical member 10 that telescopically receives a screw member 11 that is freely disposed therein and has an external diameter somewhat smaller than that of the internal diameter of the tubular sleeve 10 to permit longitudinal movement without any lateral play or displacement. Consequently, the screw member 11 will be freely displaceable within the tubular sleeve 10 which precludes any lateral movement therebetween to act as a guide therefor. The tubular sleeve 10 has an open extremity 12 to internally receive a correspondingly shaped adaptor 13 having a flanged periphery 14 which engages the open extremity 12, and an extension 15 projecting therefrom to receive work engaging member 16.

In order to preclude accidental removal between the work engaging member 16 and the adaptor shank 15, the latter is provided with radially disposed spring impelled detents 17 which cooperate with correspondingly shaped depressions 18 provided in the cylindrical bore 19 of the shank 20 integrally formed with work engaging member 16. As shown, work engaging member 16 comprises a cast, forged or otherwise shaped body which is bifurcated along a longitudinal median line to present a substantially rectangular aperture 21 to define spaced furcations 22 for the reception of a revoluble member 23 and pawl 24 retained therebetween.

The revoluble member 23 comprises a substantially circular ratchet member wheel 25 terminating in an arcuately shaped spoon-shaped projection 26 integrally formed therewith for longitudinal and lateral projection beyond the head end 27 of work engaging member 16. In order to retain revoluble member 23 for journalled rotation within body chamber 22, a stub shaft 28 is pressed into axial bore 29 provided in the revoluble member 23. The stub shaft 28 is journalled in axially aligned bores 30 and 31, provided in the furcations 22 for communication with the interior thereof.

It should be noted that aligned bores 30—31 are concentric with and adjacent to the head end 27 of bifurcated body 16 so that when stub shaft 28 is received through bores 30—31 and ratchet wheel bore 29 aligned therewith, ratchet wheel 25 will be journalled for rotation within the confines of the body cavity 21. When ratchet wheel 25 is thus assembled, the stub shaft extremities 32 and 33 will extend somewhat beyond the external wall surfaces of work engaging member 16. Split rings 34 and 35 are respectively re-

ceived in annular grooves 36 and 37 provided in the stub shaft extremities, thus precluding any substantial lateral movement of stub shaft 28 relative to work engaging member 16. The stub shaft 28 is of a high quality alloy steel that is hardened to sustain unusually heavy loads for extended periods without appreciable wear thereon.

In order to fixedly retain spoon-shaped projection 26 in the desired angular position relative to work engaging member 16, the periphery of ratchet wheel 25 is provided with radially extending ratchet teeth 38 cut or otherwise formed for extension therefrom. As shown, ratchet wheel 25 engages a correspondingly shaped circular pawl 24 longitudinally aligned therewith. Pawl 24 is received within chamber 22 ahead of ratchet wheel 25 and journaled for rotation in a manner similar to ratchet member 25. To this end, a cylindrical stub-shaft 39, having a smaller diameter than similar shaft 28, is pressed into axial bore 40 provided in pawl 24 and journaled in axially aligned bores 41 and 42 of furcations 22, in turn, longitudinally aligned with bores 30-31. The projecting shaft extremities 43 and 44 are provided with annular grooves 45 and 46, respectively, to receive split rings 47 and 48 serving as stops in precluding lateral movement of shaft 39 relative to work engaging member 16.

To enable ratcheting of the revoluble member 23 in either direction by rotary adjustment of pawl 24, said pawl has the periphery thereof interrupted to define confronting pawl teeth 49 and 50. These teeth are complementary to the ratchet teeth 38 for independent meshing engagement therewith depending upon the rotary position of the pawl 24 to control and limit the directional rotation of the ratchet member 25. The pawl teeth 49 and 50 are sufficiently spaced so that one or the other will be in operative engagement with a ratchet tooth 38 to enable the desired angular positioning of spoon 26 without interference with the inactive pawl tooth. During the ratcheting action, the pawl 24 partially rotates about its axis until the next successive ratchet tooth 38 is engaged by the active pawl tooth 49 or 50 depending upon the direction of the ratcheting action. Rotary adjustment of pawl 24 is effected by means of finger manipulating buttons 51 and 52 anchored in the periphery of pawl 24, each one being positioned an equal distance back of the pawl teeth 49-50 so as to be substantially diametrically opposed to each other.

To maintain the pawl 24 stationary and in adjusted positions for the desired directional ratcheting, a positioning ball or detent 53 is resiliently mounted on a spring 54 confined in a passage 55 provided longitudinally in the body 21 for radial communication with the pawl receiving recess 22. The spring 54 urges the positioning ball 53 in the direction of the pawl 24 for engagement with the periphery thereof. To this end, the periphery of pawl 24 is provided with conical cavities 56 and 57 for reception of the resiliently mounted positioning ball or detent 53. The cavities 56 and 57 are spaced for selective registry with the detent 53 to hold the pawl teeth 49 and 50, respectively, in meshing engagement with the teeth 38 of ratchet member 25, thereby enabling its rotation in a counterclockwise and clockwise direction (viewed from Figure 3) responsive to ratcheting or manipulating the spoon 26.

With the arrangement of parts above described, the spoon-shaped projection 26 may be rotated to the desired angular position in order to substantially correspond to the contour of indentation or irregularity in an auto body, then placed against that particular portion of the auto body to serve as an anvil in pounding out the irregularities due to impact or accident. Then, too, it may be more advantageous, in some instances, to straighten out the auto body irregularity by engaging the arcuately curved projection 26 thereover and manipulating the body jack to realign the damaged portion of the body. When the work engaging member 16 is used in this manner, fixed retention thereof in the adaptor shank 15 may be optionally effected in addition to or instead of the spring detent connection therebetween, by the provision of any suitable coupling means of the general type shown in the Downs Patent No. 1,018,172, February 20, 1912.

As a result, the work engaging projection 26 can be utilized for two-way deforming operations to bring a surface back to its initial contour with the urge exerted by the displaceable jack members 10-11 responsive to a ratcheting member, to be more fully described hereinafter. During either of these operations, the ratchet and pawl mechanism retains the spoon-shaped projection 26 in its fixed angular position and a change in position can only be effected by releasing the force exerted by the body jack and then manipulating the finger buttons 51-52 to reverse the pawl 24 and disengage ratchet member 26.

As shown in Figure 3, the engagement of pawl tooth 50 with one of the ratchet teeth 38 precludes the displacement of spoon-shaped member 26 in a counterclockwise direction. Ratchet wheel 25 is released from engagement with pawl 24 by rotating projection 26 in a clockwise direction. Further rotation in the clockwise direction is prevented by rotating pawl 24 in a counterclockwise direction through the finger manipulating buttons 51-52 until pawl tooth 49 engages a corresponding ratchet tooth 38.

The end of the tubular sleeve 10 opposite the work engaging end attachment telescopically terminates in a cylindrical reinforcing body 58 to which a knurled handle rod 59 may be connected. The extremity of knurled rod 59 (not shown) will frictionally engage the sleeve to effect tight connection between tubular sleeve 10 and its reinforcing body 58 so as to constitute a single element. A set screw 60 may be projected through reinforcing body 58 to engage the sleeve 10 and cooperate with the rod handle 59 in effecting a fixed connection between the sleeve 10 and its reinforcing body 58. Another set screw 61 projected through reinforcing body 58 engages screw member 11 so as to preclude relative rotation thereof with the sleeve 10 which are, however, axially displaceable relative to each other.

In order to displace the tubular sleeve 10 and screw member 11 inwardly or outwardly relative to each other, an improved ratcheting device 62 is provided in screw meshing engagement with screw member 11. Ratcheting device 62 and the complementary structural expedients which form cooperative members of the assembled body jack constitute no part of the present invention and are more fully described and set forth in co-pending patent application Serial No. 224,835.

filed August 13, 1938, patented Aug. 20, 1940 as Patent 2,212,090.

Screw member 11 terminates in tubular adaptor body 63 for detachable association therewith. Adaptor body 63 is interposed between screw member 11 and a suitable end bumper 64 and is connected to end bumper 64 in a similar manner to that described in connection with adaptor body 13 and the work engaging member 16. To this end, the bumper head 64 is of resilient material such as ebonite which is molded or otherwise shaped around a metallic base 65. Various other types of bumper heads may be used depending on the requirements of any particular work or which may be differed within a wide range in connection with the body jack utilized to sustain indentations and irregularities resulting through accident and impact.

The modified embodiment of the body jack attachment constituting the present invention as illustrated in Figures 4 to 7 inclusive, comprises in this instance, a work engaging member 16 having a cast, forged or otherwise shaped body of substantially circular configuration, terminating in a cylindrical shank 66. Shank 66 is provided with a cylindrical bore 67 formed with radially disposed internal depressions 68 to cooperate with correspondingly shaped spring impelled detents 17 on adaptor shank 15 (Figure 1). As shown, work engaging member 16' is bifurcated along a longitudinal median line to present a substantially rectangular aperture 69 defining spaced furcations 70 for the reception of a revolute member 71.

Revolute member 71 comprises a substantially circular plate 72 terminating in an arcuately shaped projecting member 73 integrally formed therewith for longitudinal and lateral projection beyond the head end 74 of body 16'. It should be noted that disc member 72 is retained for partial rotation within the confines of body aperture 69 while arcuately shaped member 73 integrally formed with disc member 72 projects outwardly therefrom for rotation therewith. The retention and free rotation of revolute member 71 within aperture 69 is accomplished by the provision of a pin 75 projected axially through the bore 76 located in disc member 72 so as to be concentric therewith. In turn, pin 75 is journaled in axially aligned bores 77 and 78 provided in the vertical wall surfaces of furcations 70 for communication with the interior thereof. Thus, pin 75 extends through axially aligned bores 76-77-78 so as to serve as a retaining member and fulcrum about which revolute member 71 is freely rotated.

In order that revolute member 71 may be rotated to any desired angular position within a wide circular range limited only by the abutment of arcuately shaped member 73 with the opposite end surfaces 79 and 80 of body member 16', a plurality of indexing holes 81 are provided in the confronting furcations 70 of bifurcated body member 16'. These indexing holes 81, in this instance four in number, are circumferentially spaced at predetermined angular positions intermediate the substantially circular periphery of furcations 70 and axially aligned center bores 77-78 so as to be radially equi-distant from the center bores.

When the work engaging member 16' is in assembled relation, adjustable rotary positioning of arcuately shaped member 73 is obtained by selective registry of one of the indexing holes 81 with one of a plurality of corresponding holes 82, of

equal diameter, similarly provided in disc 72. Indexing holes 82, in this instance eight in number, are equally spaced intermediate the circular periphery of disc 72 and axial bore 76 so that the equi-distant centers of said indexing holes are the same distance from the center of axial bore 76 as indexing holes 81 are from aligned center bores 77-78.

With the two series of indexing holes 81 and 82 arranged as described supra, the spoon-shaped member 73 may be angularly adjusted to any one of eight successive positions approximately $11\frac{1}{4}^{\circ}$ apart. To this end, indexing holes 82 are evenly spaced at 45° intervals so as to effect registry with one of corresponding indexing holes 81 in furcations 70. As shown in Figures 4 and 6, the initial position of spoon-shaped member 73 is obtained by registry between the lower left hand indexing holes 81a of housing 16' and the corresponding indexing hole 82a of revolute member 71 so that elongated cylindrical pin 83 may be inserted and journaled in the aligned holes 81a-82a for fixedly retaining spoon-shaped member 73 in the desired position.

By withdrawing pin 83, spoon-shaped member 73 may be rotated to any other angular position such as shown in Figure 1 in broken lines, whereby registry will be effected between indexing holes 81b and the corresponding hole 82 of revolute member 71. When the desired position has been obtained by rotation of spoon-shaped member 73 in either clockwise or counterclockwise directions (viewed from Figure 4) and the corresponding registry has been effected between indexing holes 81 and 82, pin 83 is again reinserted for retention of the predetermined angularity.

It is worthy of note that the particular arrangement of indexing holes illustrated in the accompanying drawings should be construed as illustrative rather than a limitation, since many other equally desirable correlative series of predetermined indexing hole positions will be readily apparent to those skilled in the art. In the instant showing, indexing hole 81b (Figure 4) is offset $11\frac{1}{4}^{\circ}$ in the clockwise direction from the longitudinal median line selected, for convenience, as the reference line. Indexing hole 81c is offset $22\frac{1}{2}^{\circ}$ from the reference line in the counterclockwise direction. Indexing hole 81d is offset $33\frac{3}{4}^{\circ}$ from the same line in the clockwise direction and hole 81a shown in registry with corresponding hole 82a, is offset 45° from the reference line in the counterclockwise direction.

It is apparent, therefore, that rotation of spoon-shaped member 73 in a counterclockwise direction from the initial position shown in Figures 4 and 6 will effect registry of the indexing holes 81 following in clockwise succession and a reversal of rotation results in successive registry of indexing holes 81d, 81c, and 81b in the counterclockwise order named. It should also be pointed out that axial pin 75 and position pin 83, extend somewhat beyond the external surfaces of confronting furcations 70 when the work engaging member 16' is in its completely assembled relation (see Figure 5).

In order to preclude accidental displacement of these pins 75-83 from their journaled confinement in housing 16', spring impelled detents 84 are each provided proximate to the opposite extremities of the pins for abutment against the external wall surfaces of confronting furcations 70. To this end, pins 75 and 83 are each provided with a pair of oppositely disposed recesses 85 for confinement of a pair of springs 86 to serve

as resilient support for detents 84. The detents 84, in this instance of spherical configuration, are retained within recesses 85 against accidental removal therefrom by swaging the open peripheral edges of said recesses so as to slightly diminish the diameters thereof and effectively confine the detent balls 84 therein. The pins 75-83 are inserted through the aligned bores 76-77-78 and indexing holes 81-82 by forcibly depressing the detents 84 during the movement therethrough. High quality alloy steel that is hardened to sustain unusually heavy loads for extended periods without appreciable wear thereon is the material which is preferable though not essential for use in the pins 75-83.

With the teachings of the present invention, an improved body jack end attachment is provided which may be instantly adjusted to various angles depending on the work requirements thereof. Additionally, the simple arrangement of a minimum number of parts in the assembled unit affords the rapid interchange of different lengths or types of spoons in the same housing and the replacement of worn parts with a minimum time and labor requirement.

Various changes may be made in the embodiment of the invention herein specifically defined without departing from the invention or sacrificing any features or advantages thereof, and nothing herein shall be construed as limitations of the invention, its concept or structural embodiment as to the whole or any part thereof except as defined in the appended claims.

I claim:

1. In a portable jack, the combination with longitudinally displaceable members, of means for causing the relative displacement of said members, work engaging means detachably associated with the ends of said members, one of said work engaging means including an angularly adjustable ratchet wheel, and means including a ratchet pawl for retaining said work engaging means in its selected adjustable position to carry a load.

2. In a portable jack, the combination with longitudinally displaceable members, of means for

causing the relative displacement of said members, work engaging means detachably associated with the ends of said members, one of said work engaging means including an angularly adjustable ratchet wheel, and means including a ratchet pawl for retaining said work engaging means in its selected adjustable position to carry a load.

3. In a portable jack, the combination with longitudinally displaceable members, of means for causing the relative displacement of said members, work engaging means detachably associated with the ends of said members, one of said work engaging means including an angularly adjustable element, means including a revolute ratchet wheel and a pawl for retaining said work engaging means in its selected adjustable position to carry a load, and means on said pawl for effecting the reversal thereof to afford opposite support of said ratchet wheel.

4. In a portable jack, the combination with longitudinally displaceable members, of means for causing the relative displacement of said members, work engaging means detachably associated with the ends of said members, one of said work engaging means including an angularly adjustable element, and means including an axially mounted ratchet wheel formed integral with said element, and a reversible pawl engaging said ratchet wheel for retaining said work engaging means in its selected adjustable position to carry a load.

5. In a portable jack, the combination with longitudinally displaceable members, of means for causing the relative displacement of said members, and work engaging means detachably associated with the ends of said members, one of said work engaging means including confronting intermeshing toothed elements, one of said elements having an angularly adjustable work engaging toe projecting therefrom and means for enabling the adjustment of one of said toothed elements relative to the other of said toothed elements to permit their relative rotatable displacement in a plurality of angular load carrying positions.

GEORGE M. WALRAVEN.
